UNITED STATES PATENT OFFICE.

ERASTUS ROBERT OLMSTED, OF SARATOGA SPRINGS, NEW YORK.

DESIGN FOR A KNIT-SLIPPER BLANK.

SPECIFICATION forming part of Design No. 31,023, dated June 13, 1899.

Application filed May 17, 1899. Serial No. 717,216. Term of patent 7 years.

To all whom it may concern:

Be it known that I, ERASTUS ROBERT OLMSTED, of Saratoga Springs, in the county of Saratoga and State of New York, have invented and produced a new and original Design for a Knit-Slipper Blank, of which the following is a full, clear, and exact specification.

Reference is to be had to the accompanying drawing, forming a part of this specification, in which the figure is a face view of a slipper-blank, showing my design.

The design in its entirety consists of a single ribbed upper portion A, from the top edge of which extends a narrower ribbed ankle portion B, leaving the upper portion A projecting beyond the side edges of the ankle portion B, both portions A and B appearing

with their sides extending transversely and with a number of the side ribs B' and a number of the middle ribs B² of the ankle portion appearing as single ribs, forming continuations of the corresponding single ribs of the upper portion A, the ribs B³ intermediate of the ribs B' B² appearing in groups of ribs, as shown.

The leading feature of the design consists of the ribbed upper portion and the ribbed ankle portion.

I claim—

The design for a knit-slipper blank herein shown and described.

ERASTUS ROBERT OLMSTED.
